UNITED STATES PATENT OFFICE.

ADA C. CROFFORD, OF CODY, NEBRASKA.

AUTOMATIC THREAD-TENSION-RELEASING MEANS FOR SEWING MACHINES.

Application filed August 19, 1921. Serial No. 493,613.

To all whom it may concern:

Be it known that I, ADA C. CROFFORD, a citizen of the United States, residing at Cody, in the county of Cherry and State 5 of Nebraska, have invented certain new and useful Improvements in Automatic Thread-Tension-Releasing Means for Sewing Machines, of which the following is a specification.

10 This invention relates to an automatic upper thread tension releasing means for sewing machines.

My invention relates, more particularly, 15 to sewing machines of that type wherein the upper thread tension is released when the presser foot is raised but it is not limited to use on machines of that character.

The object of my invention is to provide 20 novel means for automatically releasing the upper thread tension when the machine is turned backwardly.

To that end I provide on the cam carried 25 by the needle bar operating shaft, a swinging dog which will not be effective during the normal operation of the machine but which, when the machine is turned backwardly, will, in effect, become rigid with the cam and engage a special lever or spring which is so related to the upper 30 thread tension as to release said tension when this action occurs.

My invention is not limited to the specific 35 constructions hereinafter described and shown in the drawings as the principle of the invention may be applied in other ways, with or without the use of additional mechanical parts.

In the accompanying drawings:

Figure 1 is a side elevation, broken away, 40 showing the invention applied to a sewing machine, and

Fig. 2 is a section on line 2—2, Fig. 1.

The hollow head which contains the needle bar and presser foot is shown at 1.

45 The needle bar operating shaft 2 terminates in the hollow head 1 and carries the cam plate 3.

The upper thread tension appears at 4. This is provided with a stem 5 which passes 50 freely through the wall of the head 1 and carries a coil spring 6 which tends to hold the stem in normal position and to render the tension operative.

Secured to the head 1 and arranged vertically therein is a releasing member 7 which 55 is normally spaced or separated from the

end of the stem 5 but may be pressed against said stem for the purpose of compressing the spring 6 and releasing the thread tension 4. The releasing member 7 60 when made in the form shown, is a flat spring whose lower end is fixed to the head 1 as at 8 and whose lower portion is free and rises within said head, being provided with a curved portion 9 which lies in the 65 arc of a circle struck from the center of the shaft 2.

Pivoted at 10 to the cam plate 3 is a dog 11 which may fold into the recess or cavity 12 in the cam plate and which when thrown 70 outwardly, is arranged so that its tail will engage a shoulder 13 on the cam plate so that the dog will be rigid with the latter, if the shaft 2 is turned backwardly and the dog engages the releasing member 7. 75

During normal rotation of the shaft 2 and cam plate 3, the dog 11 is kicked back into folded position when it makes contact with the releasing member 7. When, however, the machine is turned backwardly, the shaft 80 2 and cam plate 3 rotate in reverse direction thereby throwing out the dog 11 until its tail engages the shoulder 13 whereupon the dog is rigid with the cam plate and as it engages the curved part 9 of the releasing member 7, pressing back the releasing member and causing it to engage the stem or post 5, thus releasing the tension 4. The tension remains in released condition by reason of the length of the curve 9, until the 85 dog clears the member 7. 90

I am aware that the releasing member 7 may be in the form of a lever, or in the form of a spring and that if the thread tension is differently located from the position 95 shown in the drawings, the releasing device 7 may be bent or twisted or additional links or levers employed to enable the invention to operate according to the principle explained. 100

What I claim is:

1. In a sewing machine the combination with a thread tension thereof, of a needle bar operating shaft, a releasing device adapted to cooperate with the thread tension, and a dog carried by the shaft, said dog being kicked backwardly by the releasing device during normal operation of the said shaft and rendered operative for the purpose of engaging the releasing device 110 when said shaft is turned backwardly.

2. In a sewing machine the combination

with a thread tension, of a rotary needle operating shaft having a cam, a dog pivoted to said cam and adapted to be thrown outwardly, the cam having a shoulder with which the dog is adapted to engage when thrown outwardly, and a releasing device adapted to cooperate with said thread tension and having a curved part with which said dog is adapted to engage, said dog being kicked backwardly by the releasing device during normal operation of said shaft and made rigid with the cam by engaging the shoulder when the shaft is turned backwardly, thereby pressing back the releasing device.

3. In a sewing machine, the combination with the needle operating shaft, and a cam carried by the end of said shaft, of a releasable thread tension, and a dog carried

by the cam which is automatically thrown out and made rigid with the cam when the wheel of the machine is turned backward, in which position said dog releases the thread tension.

4. In a sewing machine, the combination with the head, and the needle bar operating shaft, of a releasable thread tension having a stem, a releasing device consisting of a dog carried by said shaft, and a strip of spring steel which is rigidly fixed in the bottom of the head, is perpendicular thereto, and so placed as to be adapted to be pressed back against the inner end of the tension stem by the dog on said shaft when the machine is turned backward, to thereby release the tension.

In testimony whereof I affix my signature.
ADA C. CROFFORD.
